LAMP REPLACER

Application filed December 10, 1930. Serial No. 501,433.

Our invention has reference to devices for attaching electric lamps to or removing them from elevated sockets to obviate the necessity of employing step ladders for accomplishing this purpose, such devices being known in the art as lamp replacers.

It is a purpose of our invention to provide a lamp replacer which is characterized by its ability to receive and permit the replacing of lamps of different bulb sizes without requiring any adjustment of any part of the device, and the gripping of a lamp bulb of any size in such manner as to permit it to be manually withdrawn from the device and another inserted, all without the necessity of operating the entire device as is necessary to grip or release the lamp bulb incident to the removing or replacing the lamp from or to its socket.

We will describe only one form of lamp replacer embodying our invention, and will then point out the novel features thereof in claims.

In the accompanying drawings:

Figure 1 is a view showing in side elevation one form of lamp replacer embodying our invention and with the replacer in open or non-gripping position.

Figure 2 is a view similar to Figure 1 but showing the replacer in lamp gripping position.

Figure 3 is a view taken at right angles to Figure 2 and with a portion of the device broken away.

Figure 4 is a fragmentary view similar to Figure 2 and showing the arms of the device in gripping relation to a relatively large lamp bulb.

In carrying out our invention, we provide a handle 15 which is in the form of a pole of any desired length. Upon the upper end of the pole is secured a ferrule 16, and projecting from this ferrule is an ear 17 through which extends a pin 18 to provide a pivotal mounting for a pair of crossed levers 19 and 20.

The lever 19 beyond the pivot pin 18 is constructed to provide a pair of relatively large, curved, and divergent clamping arms 21, and a third and relatively short clamping

arm 22. This arm 22 is of a different curvature from that of the arms 21 and is offset laterally with respect thereto for a purpose to be described hereinafter.

Beyond the pivot pin 18 the lever 20 is provided with a pair of divergent and relatively short clamping arms 23 which are adapted to coact with the arms 21 as well as the arm 22 in effecting gripping of lamp bulbs of various sizes. All of the arms are covered with sleeves 24 of rubber or other suitable material in order to provide a yielding medium between the arms and a lamp bulb to prevent breaking of the latter.

Links 25 are connected to the lower ends of the levers 19 and 20, and from their points of connection with the levers they converge toward the handle 15 where they are connected to the lower end of a spring 26. This spring is of the coiled contractile type and its upper end is secured to the ferrule 16 by means of a screw 27. This screw may also be employed to secure the ferrule to the handle. The spring 26 tends to move the links upwardly and, in consequence, to move the lower ends of the levers outwardly thereby causing the two sets of arms for the respective levers to be spread to a non-gripping position with respect to a lamp bulb.

The upper end of a spring 28 is connected to the lower ends of the links 25, while the lower end of the spring is connected to the upper end of a cord 29 which extends downwardly through screw eyes 30 secured to the handle 15 for engagement with a latch head 31 provided with a base 32 secured by means of screws 33 to the handle 15 preferably at a point adjacent the lower end of the handle in order that the latch head may be readily accessible to insert or remove the cord.

The latch head 31 is provided with a V-shaped groove 34 in which the cord 29 is adapted to be received, and the cord is provided at intervals along its length with knots 35. With the cord disposed within the groove in the manner illustrated in Figure 2, any one of the knots 35 engages the latch head at the lower end of the groove so as to restrain the spring 26 against contraction to move the levers to the position shown in Figure 1.

In operation, the spring 26 causes the arms 21, 22 and 23 to normally occupy non-gripping positions with respect to a lamp bulb, that is when the spring is not expanded by downward pull on the cord 29. Thus, with the clamping arms in non-gripping position, they may be applied to a lamp bulb so that the bulb is interposed between the arms.

By pulling downwardly upon the cord the 10 links 25 are actuated to move the lower ends of the levers inwardly thereby moving the clamping arms inwardly to engage the lamp bulb, and by subsequent pulling on the handle or rotation thereof the bulb can be removed from the socket. By causing one of the knots to engage within the groove of the latch head, the cord can be maintained in lowered position to retain the clamping arms 15 in gripping engagement with the lamp bulb so that manipulation of the handle to remove the lamp from its socket can be executed with dispatch and without the liability of the arms disengaging the bulb.

With the cord 29 held in extended position 20 by the latch head 31, the spring 26 is extended so that once the cord is disengaged from the latch head the spring serves to return the clamping arms to non-gripping position. However, in practice it is desirable that the 25 cord remain latched and the clamping arms in gripping position, and particularly so where a relatively long handle is employed for the reason that the latch head being remote from the clamping arms would necessitate first the unlatching of the cord and then the holding thereof to prevent the spring 26 from moving the arms to non-gripping position and the consequent dropping of the bulb from the device.

40 To avoid this awkward method of operation with the attendant possibilities of breaking the bulb, the spring 28 is provided. With the cord latched as described and the clamping arms in gripping position, one may remove the bulb from the clamping arms by 45 manually spreading either one set of arms or the other sufficiently to allow withdrawal of the bulb from between the arms. Such movement of the clamping arms is permitted 50 by reason of the extensible connection provided by the spring 28 for it will be understood that the spring permits upward movement of the links 25 sufficiently to allow the required spreading of the clamping arms to 55 release the bulb. Conversely, a bulb may be inserted between the arms by manually spreading them, and without unlatching the cord from the latch head.

An important feature of our invention is 60 the relative arrangement of the two sets of clamping arms in order to render the devise applicable to lamp bulbs of various sizes. As illustrated, the arms 23 are disposed between the arms 21, and the curvature of the 65 two pairs of arms is such that the arms are

adapted to coact in gripping relatively large lamp bulbs, as illustrated in Figure 4. The position of the arm 22 is such that it does not engage a relatively large lamp bulb, by reason of its offset position with respect to the arms 70 21. However, the arm 21 is adapted to coact with the arms 23 in effecting gripping of relatively small lamp bulbs, as will be clear from the illustration in Figure 2. Thus the arms are adaptable to the gripping of lamp 75 bulbs of various sizes.

Although we have herein shown and described only one form of lamp replacer embodying our invention, it is to be understood that various changes and modifications may 80 be made therein without departing from the spirit of the invention and the spirit and scope of the appended claims.

We claim:

1. A lamp replacer comprising clamping 85 arms for gripping a lamp bulb, means for mounting the arms to occupy gripping and non-gripping positions, means for yieldably urging the arms to non-gripping position, manually operable means for moving the arms to gripping position, and means for latching the manually operable means to maintain the arms in gripping position, said manually operable means including a yieldable element which permits manual movement of the clamping arms to non-gripping position to permit the insertion or removal of a lamp bulb without unlatching the manually operable means.

2. A lamp replacer comprising two sets of 100 arms pivoted to occupy gripping and non-gripping positions, one of the arms of one set co-acting with those of the other to clamp a lamp bulb of one size, and the remaining arms of the first set co-acting with those of 105 the other to clamp a lamp bulb of another size when the two are in gripping position.

3. A lamp replacer comprising a pair of crossed and pivoted levers, a pair of arms on one of the levers, a pair of arms on the 110 other lever co-acting with the first pair of arms to grip relatively large bulbs, and a third arm on one of the levers positioned to coact with the arms on the other lever for gripping relatively small bulbs.

4. A lamp replacer comprising a pair of levers crossed and pivoted, a pair of arms on one of the levers, a second pair of arms on the other lever, said pairs of arms being curved inwardly, and the arms of one pair being disposed between those of the other pair, and a third arm on that lever having the pair of arms disposed to the outer sides of the other pair of arms, said arm being offset with respect to the other arms of the respective lever.

5. A lamp replacer comprising a pair of levers crossed and pivoted, a pair of arms on one of the levers, a second pair of arms on the other lever disposed to the outer sides of the 120 125 130 135 140 145 150 155 160 165 170 175 180 185 190 195 198 199 200 201 202 203 204 205 206 207 208 209 210 211 212 213 214 215 216 217 218 219 220 221 222 223 224 225 226 227 228 229 230 231 232 233 234 235 236 72222

first pair of arms, a third arm on the last mentioned lever between the respective pair of arms so as to co-act with the arms of the other lever in gripping relatively small lamp bulbs.

6. A lamp replacer comprising a pair of levers crossed and pivoted, a pair of arms on one of the levers, a second pair of arms on the other lever disposed to the outer sides
 10 of the first pair of arms, a third arm on the last mentioned lever between the respective pair of arms so as to co-act with the arms of the other lever in gripping relatively small lamp bulbs, means acting to move the levers
 15 to positions in which the arms occupy non-gripping position with respect to a lamp bulb, and means manually operable for moving the levers against the action of the first means for causing the arms to assume a gripping position with respect to a lamp bulb.

7. A lamp replacer as embodied in claim 6 wherein yieldable means is correlated to the manually operable means for permitting movement of the arms to a non-gripping position while the manually operable means is active to retain the arms in gripping position.

8. A lamp replacer comprising a handle, a ferrule on one end of the handle, a pair of levers crossed and pivoted on the ferrule, arms on said levers co-acting with the arms of the other lever to grip bulbs of another size, links connected to the levers and to each other, a spring associated with the links acting to
 30 move the levers to a position in which the arms occupy non-gripping position with respect to a bulb, a manually operable member connected to the links and mounted on the handle for actuating the links against the tension of said spring to move the levers into a position in which the arms occupy gripping position with respect to a lamp bulb, and means on the handle adapted to engage the member for latching the latter in a position
 40 in which the arms are retained in bulb gripping position.

9. A lamp replacer as embodied in claim 8 wherein a resilient member is interposed between the links and the first member providing a yieldable connection between the two so that when the member is latched to the handle the arms can be manually moved to permit the insertion or removal of a bulb to or from the arms.

55. 10. A lamp replacer comprising clamping arms for gripping a lamp bulb, means for mounting the arms to occupy gripping and non-gripping positions, means for yieldably urging the arms to non-gripping positions, manually operable means for moving the arms to gripping position, and means for so latching the manually operable means to maintain the arms in gripping position and
 60 yet permit manual movement of the arms

to non-gripping position to allow the insertion or removal of a lamp bulb without unlatching the manually operable means.
